US0D1026578S

(12) **United States Design Patent** (10) **Patent No.:** **US D1,026,578 S**
(45) **Date of Patent:** **** May 14, 2024**

(54) **INJECTOR**

(71) Applicant: **Material Girl Inc**, Omaha, NE (US)

(72) Inventor: **Brock Moller**, Bremerton, WA (US)

(73) Assignee: **Material Girl Inc**, Omaha, NE (US)

(**) Term: **15 Years**

(21) Appl. No.: **29/835,084**

(22) Filed: **Apr. 15, 2022**

(51) LOC (14) Cl. **07-04**

(52) U.S. Cl.

USPC **D7/669; D7/368**

(58) **Field of Classification Search**

(57) **CLAIM**

The ornamental design for an injector, as shown and described.

DESCRIPTION

FIG. 1 is a top front isometric view of an injector, showing my new design;

FIG. 2 is a bottom rear isometric view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left-side elevational view thereof; and,

FIG. 8 is a right-side elevational view thereof.

The broken lines in the drawings depict portions of the injector that form no part of the claimed design.

1 Claim, 7 Drawing Sheets
